WRENCH

Filed Dec. 21, 1921

Diagram showing a double-headed arrow with dimensions 16, 18, and 10 marked on its ends and body.

Fig. 6

A diagram of a cable with labels 13, 16, 18, 19, and 17. The cable is represented by a horizontal line with a hatched pattern. The labels are positioned as follows: '13' is at the left end; '16' is at the center; '18' is at the right end; '19' is at the far right end; and '17' is located between '16' and '18'.

Diagram showing a cross-section of a composite material. The total width is 30, divided into 15, 13, 14, 12, 10, 30, 15, and 13. The 14 and 12 segments are shaded.

Fig. 7.

15 13 10
21 Fig. 8.

A technical drawing of a U-shaped bracket. The top horizontal leg has a total length of 17, divided into two segments of 16 and 1. The bottom horizontal leg has a total length of 17, divided into two segments of 16 and 1. The vertical leg on the right has a total height of 191, divided into two segments of 17 and 174. The vertical leg on the left has a total height of 16, divided into two segments of 17 and 1.

A technical line drawing of a curved, elongated component. The drawing includes several numerical labels: '17' is at the left end; '16' is near the center; '18' is at the bottom right; '19' is at the top right; '20' is at the far right; '21' is at the bottom right; '22' is at the bottom right; '23' is at the bottom right; '24' is at the top right; and '25' is at the top right. There is also a label 'Fig. 9.' positioned above the component.

UNITED STATES PATENT OFFICE.

JOHN ZILLIOX, OF ORCHARD PARK, NEW YORK, ASSIGNOR OF ONE-HALF TO FRANK ZILLIOX, OF BUFFALO, NEW YORK.

WRENCH.

Application filed December 21, 1921. Serial No. 523,982.

To all whom it may concern:

Be it known that I, JOHN ZILLIOX, a citizen of the United States, residing at Orchard Park, in the county of Erie and State of New York, have invented new and useful Improvements in Wrenches, of which the following is a specification.

This invention relates to a wrench of the type commonly known as a machine wrench.

One of the objects of this invention is to provide a wrench of this character which has a removable head so that the same handle can be used in connection with a plurality of heads of different sizes, and thus permit of operating on nuts, bolts and the like of different sizes without requiring a separate compete wrench for this purpose.

Another object is to so construct the wrench that the same is very thin and compact and thus not only reaches into very narrow spaces but also takes up less room when stored or shipped.

A further object is to so construct the wrench that the same is strong and durable and can be produced in quantities at low cost.

In the accompanying drawings:

Figure 1 is a side elevation of one form of my improved wrench. Figure 2 is an edge view of the same. Figure 3 is a horizontal section of the same taken on line 3—3, Fig. 1. Figures 4 and 5 are longitudinal sections of the handle and head of the wrench similar to Fig. 3, but separated from each other. Figure 6 is a cross section taken on the correspondingly numbered line in Fig. 1. Figures 7 and 8 are perspective views of the handle and head detached from each other. Figure 9 is a side elevation, showing a modified form of my invention. Figure 10 is an edge view of a modification of my invention.

Similar characters of reference indicate corresponding parts throughout the several views.

In its general construction, this wrench comprises a head and a handle which are detachably connected with each other. As shown in Figs. 1, 2, 3, 5 and 6, the head 10

is preferably constructed of a single piece of metal which may be drop forged, cast or machined, so that the head has a socket 11 in its front end while its rear end forms a tang 12 the opposite sides of which are provided with recesses 13 which open rearwardly and form between them a narrow web 14. The front end of each of these recesses is deeper than the rear end of the same, thus forming a forwardly-facing shoulder 15 between the shallow rear and deep front parts of the same. The rear end of the web between the recesses is of tapered or wedge-shaped form as shown at 30 in Figs. 3, 5 and 8.

The handle of the wrench may be variously constructed but preferably consists of two metal bars arranged side by side and having their rear or body parts 16, 16 engaging each other and connected either by rivets 17, as shown, by spot welding, or otherwise, while the front parts 18, 18 of these bars are spread apart to form an intervening space therebetween and each bar terminating at its front end in a forwardly projecting jaw 19. In the assembling of the head and handle, the jaws of the handle are passed forwardly into the recesses of the head, so that the web is arranged between the jaws and each of the latter bears with its opposite longitudinal edges 20, 20, against the opposite parallel side walls 21, 21 of one of the recesses, thereby causing the handle and head to be firmly interlocked in the direction in which the same are turned when the wrench is used for tightening or loosening a nut, bolt or the like. The bars of the handle are preferably constructed of steel or other metal which has the requisite resilience, so that the jaws of the handle may engage frictionally with the head. This frictional engagement is promoted by bending the front ends of the jaws inwardly or toward each other, as shown in Fig. 4, so that upon passing these jaws lengthwise into the recesses the same will be first spread by the wedge-shaped rear end of the web between the recesses, and when the

45 50 55 60 65 70 75 80 85 90 95

jaws reach the foremost position in the recesses the jaws will engage with the forwardly-facing shoulders therein, as shown in Fig. 3, and thus hold the head and handle 5 tightly together in their operative relation, but still permitting the same to be readily separated by pulling the same apart manually.

The longitudinal forward movement of 10 the jaws into the recess of the head is preferably limited by the front end of the jaws engaging with the front ends of the recesses, but in addition thereto and also for producing a joint between the upper and lower 15 edges of the head and handle which will not present a sharp or dangerous edge, each of the jaws is provided on its opposite longitudinal edges with forwardly facing shoulders 22 which engage with the head at 20 the rear ends 23 of the longitudinal walls 21 of the recesses.

In Figs. 1, 7 and 8, the front ends of the jaws and recesses in the head are of round form but if desired they may be otherwise 25 shaped, as for instance in Fig. 9, where the front end of the jaw 29 and its recess 28 in the head 27 come together on a square joint.

The socket of the head may obviously be of any desired shape, the same being shown 30 for example in Figs. 1 and 8, of a form suitable for taking hold of hexagonal bolts, nuts and the like, while in Fig. 9 this socket 26 is made to take hold of corresponding members which are of square form.

35 In practice, a plurality of heads are provided each having a socket of a different shape or size than the other heads to suit different articles to be turned, thus enabling the same handle to be used with different heads and not only reducing the size of the 40 kit of tools required for doing a certain variety of work, but also effecting a corresponding reduction in cost of equipment. By using the same handle in connection 45 with a plurality of heads, a considerable saving in steel is effected compared with the amount required when each head has its individual handle.

50 Moreover, this construction of wrench is very thin, yet very strong and durable which permits the same to be packed compactly for storage and transportation, and furthermore, this wrench can be made of high grade material at low cost inasmuch as the same 55 involves comparatively simple casting or forging and stamping operations.

It is desired, the head of the wrench may be turned at an angle to the handle in order 60 to enable the wrench to reach parts ordinarily inaccessible by a straight wrench. In Fig. 10 is shown such a wrench in which the jaws or front parts 190, 191 and the head 100 removably mounted thereon are arranged at an angle of 45 degrees to the body or rear parts 16 of the handle. The

same heads can be used on handles having either straight or inclined jaws and the capacity of a kit of wrenches can therefore be doubled by the use of two handles of this character, for instance, with twelve 70 jaws of different sizes and a straight and angular handle, twenty four combinations are possible.

I claim as my invention:

1. A wrench comprising a head provided 75 on its front part with a socket and on the opposite wide sides of its rear part with recesses which extend lengthwise to the rear end of the head, and a detachable handle provided on its front end with two jaws 80 which are separated by a space extending from edge to edge of the handle and which engage frictionally with said recesses of the head.

2. A wrench comprising a head provided 85 on its front part with a socket and on the opposite wide sides of its rear part with recesses which extend lengthwise to the rear end of the head, the front ends of said recesses being deeper than the rear ends of 90 the same and forming forwardly-facing shoulders, and a handle provided at its front end with two spring jaws which are separated by a space extending from edge to edge of the handle and which are adapted 95 to enter said recesses and which have their front ends bent toward each other and adapted to engage the shoulders in said recesses.

3. A wrench comprising a head provided 100 on its front part with a socket and on the opposite wide sides of its rear part with recesses which extend lengthwise to the rear end of the head, and a handle provided on its front end with two jaws which are separated by a space extending from edge to 105 edge of the handle and which engage with said recesses of the head and at the rear end of said jaws with forwardly facing shoulders which are adapted to engage with the rear end of said head. 110

4. A wrench comprising a head provided on its front part with a socket and on opposite sides of its rear part with recesses forming between them a web the rear end of which is wedge-shaped, and a handle provided at its front end with two jaws which are adapted to be spread by the wedge-shaped rear end of said web and to enter 115 said recesses upon assembling the same.

5. A wrench comprising a head provided 120 on its front part with a socket and on opposite sides of its rear part with recesses, the front ends of said recesses being deeper than the rear ends of the same and forming forwardly-facing shoulders and said recesses forming between them a web the rear end of which is wedge-shaped, and a handle provided at its front end with two inwardly-bent spring jaws which are adapted to be 125 spread by engagement with the wedge- 130

shaped rear end of said web and to enter said recesses and engage the shoulders therein.

6. A wrench comprising a head having recesses in opposite flat sides which extend to the rear end of the head, and a handle composed of two bars which are arranged side by side and having their rear parts con-

nected together while their front parts are spread apart perpendicular to the plane of the wide sides thereof and form two forwardly projecting flat jaws, which engage with the recesses on the opposite sides by said head.

JOHN ZILLIOX.
